AT&T

UNITED STATES PATENT OFFICE.

GUSTAVUS WIDEMAN, OF AURORA, ILLINOIS, ASSIGNOR TO WILCOX MANUFACTURING COMPANY, OF AURORA, ILLINOIS, A CORPORATION OF ILLINOIS.

CARRIER-TRACK.

SPECIFICATION forming part of Letters Patent No. 693,934, dated February 25, 1902.

Application filed August 26, 1901. Serial No. 73,873. (No model.)

To all whom it may concern:

Be it known that I, GUSTAVUS WIDEMAN, a citizen of the United States, residing at Aurora, in the county of Kane and State of Illinois, have invented certain new and useful Improvements in Carrier-Tracks, of which the following is a specification, reference being had to the accompanying drawings.

This invention relates to improvements in overhead tracks adapted to receive and support a suitable trolley, from which may be permanently or removably suspended any article that it is desired to move from place to place. In the accompanying drawings I have shown my improved track in use in connection with a trolley to which is attached an ordinary store-ladder, and for such use, as well as for other indoor uses, it is especially well adapted, although it may advantageously be employed in other situations. Many of the tracks employed for indoor purposes are of the tubular variety, in which a slot at the bottom is provided for the passage of the depending hanger-arm, the oppositely-located wheels of the trolley running upon tracks formed by the inwardly-turned sides of the tube. While such constructions constitute very efficient tracks, they are open to the objection of being more or less noisy owing to the reverberations of sound caused by the tubular form of the track. With my improved form of track this objection is obviated and at the same time a very strong track is produced which can be cheaply and easily made, can be readily applied in place, and can also be easily kept clean. I accomplish this by the means shown in the drawings and herein-after described.

In the drawings, Figure 1 is a perspective view of a length of my improved track with a trolley placed thereon to which is suspended a store-ladder. Fig. 2 is a side elevation of the track, showing also a portion of the trolley and ladder attachment shown in Fig. 1; and Fig. 3 is an end elevation of the parts shown in Fig. 2, the track and one of the trolley-wheels being in section.

Referring to the drawings, A indicates my improved track, which in the form of con-

struction shown is composed of two pieces a a 50 of sheet metal each bent or curved near its lower end to form suitably-shaped tracks or ways b b and curved or bent near its upper end to form guards c c over the trolley-wheels when the same are placed on the tracks or ways a a 55 and acting to prevent the accidental displacement of the trolley-wheels from the tracks or ways b b. These pieces a a in the form of construction shown are placed with their vertical portions, which constitute the 60 main or body portion of the device, back to back, as illustrated, and firmly secured together by rivets d or in any other suitable manner, the portions b and c of each piece a consequently projecting outward in an opposite direction from the corresponding portions on the other piece a.

B B indicate two pairs of trolley-wheels adapted to be entered from the end of the track A and run on the tracks or ways a a. 70 Each pair, as shown, is connected by a curved hanger-strap C, through each end of which passes the projecting end of an axle e of one of the wheels B, such wheels, of course, turning freely on their respective axles. 75

D indicates an ordinary ladder, to the upper end of which is firmly affixed an angular frame E, that fits between the two parallel curved hanger-straps C and affords a means through which the ladder is connected to the 80 said straps C.

That which I claim as my invention, and desire to secure by Letters Patent, is—

1. In a carrier-track, the combination of two strips of material arranged parallel with 85 each other and each having its lower portion extended outwardly to form a track or way and its upper portion bent at right angles to form a guard.

2. In a carrier-track, the combination of 90 two strips of metal arranged parallel with each other and each having its lower portion extended outwardly to form a track or way, substantially as specified.

3. In a carrier-track, the combination of 95 two strips of metal arranged parallel with, abutting against each other and each having its lower portion bent or curved outwardly to

form a track or way, and means for securing said strips together, substantially as specified.

4. In a carrier-track, the combination of 5 two strips of metal arranged parallel with each other and secured together, each strip being turned at its lower portion to form an outwardly-extending track or way, and also turned at its upper portion to form an outwardly-extending guard over the track or way 10 at the lower portion of the strip, substantially as specified.

5. In a carrier-track, the combination of two strips of material arranged parallel with 15 each other and each having its lower portion

extending outwardly in a curved manner to form a track or way and its upper portion bent at right angles to form a guard.

6. In a carrier-track, the combination of two strips of material arranged parallel with 20 each other and each having its lower portion extending outwardly in a curved manner to form a track or way and its upper portion bent at right angles to form a guard, and means for securing the two strips of material 25 together.

GUSTAVUS WIDEMAN.
